UNITED STATES PATENT OFFICE.

RUSSELL J. TURNER, OF YOUNGSTOWN, OHIO, ASSIGNOR OF ONE-HALF TO C. T. GAITHER, OF YOUNGSTOWN, OHIO.

DISK VEHICLE-WHEEL.

1,380,873.

Specification of Letters Patent. Patented June 7, 1921.

Application filed July 16, 1920. Serial No. 396,851.

To all whom it may concern:

Be it known that I, RUSSELL J. TURNER, citizen of the United States of America, residing at Youngstown, in the county of 5 Mahoning and State of Ohio, have invented certain new and useful Improvements in Disk Vehicle-Wheels, of which the following is a specification.

This invention relates to improvements in 10 vehicle wheels, and especially of wheels for automobiles of the steel disk type.

The principal object is to provide a wheel of extremely simple construction, and at the same time producing a wheel that is strong, 15 durable and low in manufacturing costs.

Another object is to provide a disk wheel using the ordinary artillery wheel hub with one flange eliminated.

A still further object is to provide a disk 20 wheel with the front disk without a central opening and fitting over the outer hub end at a tension.

With these and other objects in view, the invention consists in the construction and 25 novel combination of parts hereinafter fully described, illustrated in the accompanying drawing, and pointed out in the claims here- to appended, it being understood that various changes in the form, and minor details 30 of construction, within the scope of the claims, may be resorted to without departing from the spirit or sacrificing any of the advantages of the invention.

In the drawing:—

35 Figure 1 is an edge view of the wheel partly in section.

Fig. 2 is front view of the wheel.

Fig. 3 is a detailed sectional view showing a boss on the outer disk.

40 It will be seen by referring to Fig. 1 that I have provided an ordinary hub 1 with the inner flange 2. Fastened to the flange 2 by rivets 3 or any other desirable means is the rear disk 4. It will be seen that this 45 disk 4 is fastened on the inner surface of the flange 2, and that an inturned portion of the disk 4 forms a collar 5 fitting securely around the hub 1. This disk 4 is provided with a felly band seat 6 and an outwardly 50 curved tire retaining flange 7.

By referring to Figs. 1 and 2 it will be

seen that the front disk 8 is without a central opening and presses securely against the outer end 9 of the hub 1. This front disk 8 is provided with a felly band seat 10 and an outwardly curved tire retaining flange 11.

In assembling the parts of this improved disk wheel, the disk 4 is slipped over the end 9 of the hub 1 and securely fastened to 60 the flange 2. This disk 4 is made with a very slight concave inner portion or part within the rim. The felly band 12 is now placed in the felly seat 6 and the front disk 8 is then placed in position and the bolts 13, 65 which pass through the disks 4 and 8 respectively, are tightened. As this tightening process is progressing the central portion of the disk 8 is drawn tight against the hub end 9 due to the very slight con- 70 cave portion of the disk 4.

It will be seen by referring to Fig. 1 that the felly band 12 is forced against the felly seats 7 and 10, thereby eliminating the possibility of an imperfect contact. When 75 these bolts 13 are properly tightened the entire wheel assembly becomes securely fixed, with the disks 4 and 8 at a tension. thereby securing strength and eliminating 80 the chance for rattle found in other types of wheels.

While I have not shown the opening for a valve stem, I prefer to use an ordinary angle stem passing through an opening at any convenient point in the inturned portion 14 of the disk 8.

By using a relatively light felly band 12 the heat produced in the tire will be rapidly carried away through said felly band 12.

It is understood, that if desired, the central portion of the disk 8 may be provided with a boss 14 so that the end 9 of the hub 1 may be seated within the space formed by said boss.

What I claim is:

1. In a device of the class described, the combination of a hub, an inner flange on said hub, a rear disk secured to said flange, a collar formed on said disk and fitting around said hub, a front disk without a central opening, a boss centrally located on said front disk, said boss wedging se-

curely over the outer end of said hub, bolts passing through disks, substantially as described for the purpose set forth.

2. In a device of the class described, two disks, an inner disk provided with a central opening, an inturned collar passing over a hub and secured to a flange, an outer disk, a boss centrally located in said disk,

means for securing said disks in relation to each other.

10

In testimony whereof I affix my signature.

RUSSELL J. TURNER.
